US0D1037871S

(12) **United States Design Patent** (10) Patent No.: **US D1,037,871 S**
(45) Date of Patent: ** Aug. 6, 2024

(54) **PACKAGING**

(71) Applicant: **JUUL Labs, Inc.**, San Francisco, CA (US)

(72) Inventors: **Rajeev Bhalla**, Palo Alto, CA (US); **Jason Curtis**, Alameda, CA (US); **Peter C. De Alva**, Lake Zurich, IL (US); **Pyiphyo Lwin**, Newark, CA (US); **James Monsees**, San Francisco, CA (US); **Kevin J. Myers**, San Jose, CA (US); **Vincent C. Phua**, Piedmont, CA (US); **Jambunathan Vangal Ramamurthy**, San Jose, CA (US); **Alexandra N. Siano**, San Francisco, CA (US); **Srinivasan Sundararajan**, Cupertino, CA (US); **Bryan White**, Pleasanton, CA (US); **Thomas J. White**, Pebble Beach, CA (US)

(73) Assignee: **Juul Labs, Inc.**, Washington, DC (US)

(**) Term: **15 Years**

(21) Appl. No.: **29/737,360**

(22) Filed: **Jun. 8, 2020**

Related U.S. Application Data

(63) Continuation of application No. 29/659,407, filed on Aug. 8, 2018, now Pat. No. Des. 886,638.

(51) **LOC (14) Cl.** **09-03**

(57) CLAIM

The ornamental design for a packaging, as shown and described.

DESCRIPTION

FIG. 1 is a bottom, front, and right side perspective view of a packaging of our design;

FIG. 2 is a bottom, front, and left side perspective view thereof;

FIG. 3 is a front view thereof;

FIG. 4 is a rear view thereof;

FIG. 5 is a right side view thereof;

FIG. 6 is a left side view thereof;

FIG. 7 is a bottom view thereof; and,

FIG. 8 is a top view thereof.

The long dash-dash broken lines illustrate perforations that form a part of the claimed design.
